MEANS FOR SUPPORTING AND OPERATING
STIRRERS FOR GLASS IN A FOREHEARTH

Edward T. Ross, Granby, Conn., assignor to Emhart Manufacturing Company, a corporation of Delaware

Application January 10, 1950, Serial No. 137,700

4 Claims. (Cl. 259—104)

1

This invention relates to improvements in means for operatively supporting and rotating a vertical stirrer or stirrers for molten glass in a forehearth.

An object of the invention is to provide improved means of the character described having conveniently and quickly usable means to raise the stirrer or stirrers to a level above the forehearth when desired for examination or removal thereof and for returning the stirrer or stirrers or replacements thereof to operative position in the forehearth.

A further object of the invention is to provide improved means of the character described having a stirrer operating mechanism which is constructed and arranged to rotate the stirrers when they are in their lowered working position in a forehearth and automatically to stop their rotation when they are raised from their working position.

A still further object of the invention is the provision in means of the character described of means automatically to limit the upward and downward movements of the stirrers.

Other objects and advantages of the invention hereinafter will be pointed out or will become apparent from the following description of a practical embodiment thereof as shown in the accompanying drawings, in which:

Figure 1 is a fragmentary plan view of a portion of a glass forehearth equipped with stirrers and stirrer operating and supporting means embodying the invention;

Fig. 2 is a transverse vertical section through the portion of the forehearth shown in Fig. 1 with the stirrers and their supporting and operating means shown in front elevation;

Fig. 3 is a relatively enlarged view, mainly in vertical section and partly in elevation, of means to raise and lower a stirrer spindle supporting arm of the stirrer supporting mechanism and associated means for rotating the stirrers;

Fig. 4 is a plan view of an end portion of the stirrer spindle supporting arm and of a cooperative upright guideway member for such arm, showing also elements of the stirrer rotating mechanism;

Fig. 5 is a still further enlarged fragmentary section view of a clutch which is included in the stirrer rotating mechanism; and

Fig. 6 is a diagram of the electrical mechanisms and connections of means for controlling the operations of the stirrer raising and lowering and stirrer rotating mechanisms.

A fragmentary portion of a glass forehearth is 55 assembly of the slidably associated parts.

2

indicated generally at 1 in Fig. 1 and is shown in section in Fig. 2. This forehearth includes a refractory glass flow channel 2 which in use contains a stream of molten glass (not shown) in which depend the glass engaging lower end portions 3a of refractory glass stirrers 3. These glass stirrers 3 extend through a gap 4 in the roof 5 of a cover structure 6 of the forehearth. The channel 2 is disposed in a metallic casing 7 from which it is spaced by suitable refractory and/or heat insulating material represented by blocks indicated at 8 in Fig. 2, as is usual in a conventional forehearth structure. The casing 7 may be supported by any suitable supporting means (not shown).

The upper ends of the stirrers 3 project above the gap 4 in the forehearth roof and suitable pairs of relatively front and rear cover blocks 9 and 10, respectively, may be provided on the 20 forehearth roof substantially to cover the top of the gap 4 around the upper end portions of the stirrers 3. The cover blocks 9 and 10 are cooperatively notched to define suitable circular openings, such as indicated at 11, Figs. 1 and 2, having walls fitting rather closely around the projecting upper end portions of the stirrers 3 when the cover blocks are closed as shown in that view. The glass engaging lower end portions 3a of the stirrers are formed with spiral projections 12 thereon and when the stirrers are to be raised from the forehearth, the cover blocks 9 and 10 are moved apart to permit this operation.

The stirrers 3 are suspended by having their upper ends held in chucks 13 which are detachably connected by couplings 14 to the lower ends of vertical rotary spindles 15 which are operatively mounted on an overhanging stirrer spindle cross arm 16. This may be accomplished by use of suitable supporting bearings on the arm 16, as, for example, upper and lower vertically aligned bearings 17 and 18, respectively.

The stirrer spindle arm 16 has a supporting end portion 16a formed integrally with or operatively connected in any other suitable known way to the upper end of a generally vertical slidable carrier 19. The outer vertical side portion of the carrier 19 is generally T-shaped in transverse section as indicated at 19a, Fig. 4, and fits slidably in a vertical complementarily shaped guideway 20 in the adjacent side of an upright stationary support 21. The walls of the guideway 20 may include removable vertical gib strips 22, fastened in place by cap screws 23, to permit dis-

The stationary guideway member 21 extends upwardly from and may be joined integrally or otherwise to a housing 24 which is supported in a fixed position at one side of the forehearth channel. As shown in Fig. 2, the housing 24 is provided at its inner side with an upper bracket 25 attached by appropriate fastening means 26 to an outturned flange 27 at the upper edge of a side of the forehearth channel casing 7. The housing 24 also may have lower attaching ears or portions, such as indicated at 28, attached by fastening means 29 to a supporting channel member 30 which in turn is welded or otherwise rigidly secured to the adjacent side of the channel casing 7. The housing 24 has a bottom opening, as indicated at 24a, Fig. 3, so that a driven vertical shaft 31 may project thereinto from below. This shaft is driven by a speed reduction unit 32 which has an operatively driven connection with a reversible motor 33. The entire unit comprising the motor 33, the speed reduction unit 32 and the upturned driven shaft 31 may be supported in place by a suitable bracket 34 on the reduction gear unit attached, as by the fastening means 35, to the bottom portion of the housing 24 surrounding the opening 24a.

Within the housing 24, the upper end of the driven shaft 31 is connected by a suitable coupling 36 to the lower end of a vertical jack screw 37 which extends upwardly within a vertical space 38 in the vertically movable carrier 19 which is appropriately hollow. A nut 39 through which the jack screw 37 is threaded fits in an opening 40 in the lower end portion of the hollow carrier 19 to which it is fixed by suitable fastening means 41. It is apparent that rotation of the jack screw 37 about its axis in one direction will raise the slidable carrier 19 and about its axis in the opposite direction will lower the carrier. The stirrer spindle arm 16 and the stirrers suspended therefrom will move with the carrier 19 on its upward and downward movements. The stirrer spindle arm 16 has a free end section, indicated at 16b, Fig. 2, positioned in part in an open topped slot 42 in a laterally projecting bracket arm 43 on a stationary upright 44 at the side of the forehearth opposite the slide 19 when the arm 16 is in its lowered position and the stirrers 3 are in their operative position in the forehearth channel as shown in Fig. 2. At this time, a clamping screw 45 which is threaded through a side wall 42a of the slot 42 may be tightened by its handle or head portion 45a against the portion of the stirrer spindle arm end section 16b in the slot to clamp the latter firmly against a projection 46 on the opposite side wall 42b of the slot so as to stabilize the position of the stirrer spindle arm. The clamping screw 45 will be loosened when the stirrer spindle arm is to be raised. The upright 44 may be carried by a suitable bracket 47 on the side of the forehearth casing 7 opposite the housing 24.

The upper ends of the stirrer spindles 15 carry sprockets 48. An endless chain 49 is trained about these sprockets and about suitably located idle guiding sprockets 50 and 51, respectively, on the arm 16 and a driven sprocket 52 on a driving spindle 53. The spindle 53 is rotatably mounted, as by upper and lower bearings 54 and 55, respectively, in a bearing box 56, Fig. 3, which is provided with a bracket portion 57 secured in place, as by cap screws 58, Figs. 3 and 4, on the attaching end portion 16a of the stirrer spindle arm 16. A chain tightening idle sprocket 59 may be adjustably mounted on the arm end section 75

16a, as by the slidably adjustable supporting means, indicated at 60, Fig. 4, to aid in guiding the chain 49 and to maintain it desirably taut.

The mechanism for driving the spindle 53 to drive the chain 49 and the stirrer spindles 15 comprises a motor 61, Fig. 3, connected by a speed reduction unit 62, an overload release clutch 63 and a universal joint 64 with a lower rod-like section 65 of a drive shaft which also includes a tubular upper section 66 connected by a universal joint 67 with the lower end of the spindle 53. The tubular upper section 66 fits slidably over the upper end and a substantial part of the length of the rod-like section 65. A driven clutch element 68 of a clutch of a single jaw variety is fixed on the lower end of the tubular upper section 66 in confronting relation to a cooperative driving clutch element 69 on the rod-like section 65. The clutch element 69 is mounted for limited sliding movement on the member 65, this movement being limited by a conventional slot and pin arrangement indicated at 70. See also Fig. 5. Rotation of the clutch element 69 on the rod-like member 65 is prevented by a spline 71 which is fast on the member 65 and fits slidably in a splineway 72 in the clutch element. A compression coil spring 73 is disposed around the member 65 between the lower end portion of the clutch element 69 and a lower positioned washer 74 or other abutment on the member 65 and tends to maintain the clutch element 69 continuously at the upper limit of its path of movement on the member 65. The arrangement is such that when the carrier 19 is raised from its lowered position, shown by full lines in Fig. 3, as indicated by the dot-and-dash line showing of its upper end in the same view, the tubular section 66 of the drive shaft will be raised with it, thereby moving the clutch element 68 out of engagement with the clutch element 69 and stopping rotation of the spindle 53 and hence of the stirrers. This will take place on a slight upward movement of the carrier 19. On a downward return movement of the carrier 19, the clutch element 68 will be guided into engagement with the spring pressed cooperative clutch member 69 so that driving of the stirrers will be resumed, provided, of course, that the motor 61 is in operation.

Raising and lowering of the arm 16 and of the stirrers suspended therefrom are facilitated by a counterweight 75 suspended from one end of a cable 76 which passes over suitably spaced supporting and guiding sheaves 77 and 78, respectively, on an overhead supporting frame structure 79 above the forehearth, the other end of the cable 76 being attached to the middle portion of the arm 16, as by an attaching eye 80.

The upward and downward movements of the stirrers are limited by suitable electrical controls for the reversible elevating motor 33. These include a double-throw limit switch 81, Fig. 6, having a suitably positioned pivoted angular or two-armed operating member 82 operable by a projecting rigid actuator 83 on the carrier 19 and a single-throw limit switch 84 having a similar pivoted angular or two-armed operating member 85 operable by a projecting rigid actuator 86 also on the carrier 19. The limit switch 81 has at one side a pair of spaced contacts 87 and 88, respectively, connected by a wire 89 to one side of a push button "run" switch 90 and by a wire 91 to one side of a push button "stop" switch 92, the other side of which is connected by a wire 93 to

one of three main power lines 94, 95 and 96, respectively. The other side of the limit switch 81 has two spaced contacts 97 and 98, respectively. The contact 97 is connected by a wire 99 to one side of a "lower" push button switch 100. The contact 98 is connected by the wire 91 to the "stop" switch 92. The limit switch 84 has two spaced contacts 101 and 102, respectively. The contact 101 is connected by a wire 103 to one side of a "raise" push button switch 104. The "raise" switch 104 and the "lower" switch 100 are operatively connected to "raise contactor and interlock" and "lower contactor and interlock" assemblies 105 and 106, respectively, of a known reversing switch. This, in the example shown, is manufactured by Allen-Bradley Co. of Milwaukee, Wisconsin, and is known as the Allen-Bradley reversing switch, style RT, size 00, Nema type 1, Bulletin 705. The "run" switch 90 controls a "starter contactor and interlock" assembly 107 of a known starting switch, as for example, the Allen-Bradley starting switch, form 2, size 0, Nema type 1, Bulletin 709. The reversing switch and the starting switch are operatively connected with the power input lines 94, 95 and 96. The reversing switch is operatively connected with the elevating motor 33 and the starting switch is operatively connected with the stirrer motor 61. Any suitable or preferred arrangement of suitable electrical mechanisms and connections may be used to control the operations of the elevating and stirrer motors.

With the stirrers in their working positions down in the forehearth channel, the limit switch 81 will be closed through the contacts 87 and 88 and open at the contacts 97-98. The limit switch 84 will be closed. The stirrer motor 61 will be running and the elevating motor 33 will be at rest. To elevate the stirrers, the operator may first press the "stop" switch button, stopping the stirrer motor. Then by pressing the "raise" switch button, the motor 33 will be started to operate in the direction required to raise the carrier 19 and the stirrers from the forehearth channel. If the operator should not first press the "stop" switch button, as is preferred, the upward movement of the carrier will be attended almost immediately by stoppage of the stirrer motor since the actuator 83 will contact the switch operating member 82 of limit switch 81 so as to open the motor operating circuit which includes the contacts 87 and 88 when the carrier has traveled upward a very short distance, say approximately $\frac{3}{4}$ of an inch. This also will close the limit switch 81 through its contacts 97-98 to prepare it for subsequent use in lowering the carrier. The upward movement of the carrier 19 will continue until the actuator 86 opens the limit switch 84, thereby stopping the elevating motor. The stirrers will then be in their raised position and may be inspected and removed conveniently and replaced by new stirrers if required.

To lower the stirrers or their replacements, the operator presses the "lower" switch button and the elevating motor will be started in its reverse direction. The operating circuit to cause this operation includes the limit switch 81, closed through its contacts 97-98. The carrier 19 will be lowered until the actuator 83 engages the second arm of the pivoted switch operating member 82 and opens the circuit at the contacts 97, 98 of the limit switch 81. This also will prepare the limit switch 81 for use in the operating circuit for the stirrer motor when the latter has been

re-started by closing of the push button "run" switch.

The actuating element 86 on the carrier will trip the operating member 85 of the limit switch 84 at the beginning of downward travel of the carrier to close such limit switch in preparation for the next carrier raising operation.

By pressing the "lower" switch push button and the "stop" switch push button repeatedly and alternately, the control mechanism may be actuated to lower the stirrers step-by-step a few inches at a time so that they will become gradually heated during their downward travel so as to eliminate heat shock.

When the downward travel of the carrier 19 has ended, the stirrers will be in their fully lowered working positions in the forehearth channel. The operator may re-start the stirrer motor by pressing the button of the "run" switch 90.

The several push button switches may be located in a push button switch box conveniently mounted on the stationary support 21, as indicated at 108 in Fig. 2.

The levels at which the upward and downward movements of the carrier will be stopped may be varied within limits, as by varying the levels at which the limit switches will be tripped to stop travel of the carrier. This may be accomplished by mounting the limit switch actuators on the carrier by vertical slot and fastening screw arrangements such as indicated at 109 for actuator 86 in Fig. 2 or by any other known or preferred height adjusting arrangement.

The particular embodiment of the invention shown in the drawings and herein particularly described obviously may be altered and modified in ways which now will be obvious to those skilled in the art and I, therefore, do not wish to be limited to the details of this embodiment.

40 I claim:

1. Supporting and operating means for an implement, comprising a supporting arm, rotary means mounted on said arm to suspend the implement from said arm to hang vertically therebelow when the arm is horizontal and for rotation about its own axis, a vertically movable carrier rigidly joined to one end of said arm, means located at one side of a forehearth to guide said carrier for vertical movements relative to the forehearth and for engagement with the carrier to maintain said arm substantially horizontal and in a transversely extending overhanging relation to the forehearth, driving means, including a reversible electric motor, operatively connected to the carrier to move it vertically at will to move the implement suspended from said arm between a lowered, working position in the forehearth and a raised position above the forehearth, other driving means, including a separate motor, connected to the rotary means mounted on said arm to rotate said implement about its axis when said implement is in its lowered, working position in the forehearth, and electric control means for said reversible electric motor, including limit switches, operable automatically to stop the operation of said reversible motor when the carrier has been moved to its raised and lowered positions, respectively.

2. Supporting and operating means for an implement, as defined by claim 1, wherein said carrier is hollow so as to provide a vertically extending space therein, and said driving means for the carrier includes a nut fast to the carrier at the 70 lower end of said space and an upright jack screw

having a driven connection with the reversible motor and threaded through said nut into said space in the carrier.

3. Supporting and operating means for an implement, as defined by claim 1, wherein said rotary means mounted on said arm comprises a rotary element adapted to be made fast to the implement and co-axial therewith, and said driving means therefor comprises a rotary driving element carried by the supporting arm adjacent to the carrier, means connecting said rotary elements to impart rotation to the first when the second-named rotary element is rotated, a rotary shaft having an upper section operatively connected at its upper end with the second-named rotary element and a lower section operatively connected at its lower end with the second-named motor, said shaft sections telescopically overlapping each other, and cooperative clutch members respectively carried by the shaft sections in positions such that they are engaged with each other when the carrier is at the lower limit of its path of vertical movements and are disengaged when the carrier is raised from that position.

4. Supporting and operating means of the character described, comprising a horizontal supporting arm, a plurality of individually rotatable vertical spindles mounted on said horizontal supporting arm to carry implements in a transverse row in a forehearth when the arm is disposed in a transversely extending position above the forehearth at a predetermined level thereabove, a

5
